G. A. HURLEY

SHANK STIFFENER FOR SHOES

Filed April 18, 1923

Inventor.
George A. Hurley
G. A. HURLEY

UNITED STATES PATENT OFFICE.

GEORGE A. HURLEY, OF ROCKLAND, MASSACHUSETTS.

SHANK STIFFENER FOR SHOES.

Application filed April 18, 1923. Serial No. 632,990.

This invention relates to shank stiffeners for shoes and has for its object a shank stiffener of composite construction arranged to provide exceptional stiffness and support to the shank-portion of the shoe.

A further object is a shank stiffener constructed and arranged to provide a substantial support for the ball-portion of the shoe compared with the support provided by the common form of shank stiffener.

Fig. 1 is a plan view of a shank stiffener embodying the invention.

Fig. 2 is a plan view of the shaped or molded base-member of the stiffener.

Fig. 3 is a plan view of a reinforcing member adapted to be received within the recess in the upper face of the base-member.

Fig. 4 is a longitudinal section along line 4—4 of Fig. 1.

Fig. 5 is a transverse section along line 5—5 of Fig. 1.

Fig. 6 is a transverse section along line 6—6 of Fig. 2.

Fig. 7 is a transverse section along line 7—7 of Fig. 3.

As here shown, the shank stiffener embodying the invention comprises a base-member 10 which may be made of fibre or other suitable material and has a more or less usual outline. Said base member is formed or molded with a raised middle portion 11 on its lower face, and said raised portion extends longitudinally of the base-member for the major portion of its length; and the forward end of said raised portion is extended laterally toward the inner forward edge, or directed into the ball-supporting portion, 12 of the stiffener. This construction of the fibre base-member serves to reinforce and strengthen it and impart enhanced resistance to buckling and also provides substantial support for the ball-supporting portion of the shoe. Said base-member is also formed with an indentation or recess 13 in its upper face which corresponds to and is complementary with the raised portion of the lower face; and said recess also extends into the ball-supporting portion of the stiffener, as at 13^a. A re-inforcing and filler member 14 is arranged to occupy said recess and is shaped to conform to said recess and, for this purpose, is formed or provided with the more or less V-shaped bottom face 14^a and the curved or laterally-extended forward-end portion 14^b which is adapted to enter the lateral portion 13^a of said recess. The upper

face 14^c of said member is preferably flat and the thickness of said member preferably is such that, when said member is received within the recess 13 of said base-member, the upper face 14^a is approximately flush with the upper face of said base-member. Said re-inforcing member is preferably made of fibre or other suitable and preferably non-metallic material and may be secured to said base-member in any suitable manner as by tacks 16 or by an adhesive, or both, and in such a manner that said re-inforcing member provides a substantial support for and increases the strength of said base-member. Said re-inforcing member also serves as a filler for the recess in said base-member.

The shank-stiffener is also provided with a reinforcing stiffening plate 15 which preferably is made of steel or some other strong material, as contrasted with the material of which said base and filler members are composed. Said plate 15 is relatively long and narrow and is disposed mainly along the longitudinal line of the base-member and upon said fibre re-inforcing member 14, and lies preferably within the boundaries of said base-member. Said plate 15 is secured to said fibre base-member and also to said fibre re-inforcing member by the tacks 16, which tacks may also secure together said base and reinforcing members. Said plate 15 is formed with the laterally extended or curved forward end-portion 15^a which extends over the ball-supporting portion of the shank-stiffener and is arranged to increase the stiffness of the stiffener thereat.

It is to be noted that the fibre re-inforcing member 14 provides means by which the metal stiffening plate may be applied in an effective manner to the shaped fibre stiffener.

I claim:

1. A shank stiffener for shoes comprising the combination of a base-member having a raised re-inforcing portion extended longitudinally in its lower face, and a corresponding recess in its upper face, a re-inforcing and filler member disposed in said recess approximately flush with the upper face and secured to said base-member, and a metal re-inforcing plate extended longitudinally of and located within the ends of the stiffener over said filler member, and secured to said filler and base members.

2. A shank stiffener for shoes comprising the combination of a fibre base-member hav-

ing a raised re-inforcing portion extended longitudinally in its lower face, and a corresponding recess in its upper face, and means to stiffen said base-member comprising a metal re-inforcing plate extended longitudinally of the stiffener over said recess, and a fibre re-inforcing and filler member received in said recess and under said plate and secured to said plate and base-member.

10 3. A shank stiffener for shoes comprising the combination of a base member comprising a ball-supporting portion and having a longitudinally extended raised portion in one face, and a corresponding recessed portion in its opposite face, and a flat, longitudinally-extended, metal re-inforcing plate secured to said base member over said recess and having a lateral forward end-extension disposed over the ball-supporting portion of
15 said base member.

20 said base-member.

4. A shank stiffener for shoes comprising the combination of a base-member having a raised re-inforcing portion extended longitudinally in its lower face, and a corresponding recess in its upper face, a re-inforcing and filler member disposed in said recess approximately flush with the upper face, and secured to said base-member, and a metal re-inforcing plate extended longitudinally of 25 and located within the ends of the stiffener over said filler member and secured to said filler and base members, said metal re-inforcing plate having a lateral end-extension disposed over the ball-supporting portion of 30 said base-member.

35

5. A shank stiffener for shoes comprising the combination of a base-member having a

raised re-inforcing portion extended longitudinally in its lower face, and a corresponding recess in its upper face, a re-inforcing and filler member disposed in said recess approximately flush with the upper face and secured to said base-member, and a metal re-inforcing plate extended longitudinally of and located within the ends of the stiffener over said filler member and secured to said filler and base members, said metal re-inforcing plate having a lateral end-extension disposed over the inner end-portion of said base member. 40 45 50

6. A shank stiffener for shoes comprising the combination of a fibre base member having a raised re-inforcing portion in its lower face and an upper face formed with a corresponding depression, said raised portion and recess extended longitudinally along the major portion of said base-member and laterally at the forward edge of said base-member into the inner edge-portion thereof, a fibre re-inforcing and filler member disposed in the longitudinal and lateral portions of said recess, and approximately flush with the upper portion of said base-member, and secured to said base-member, and a metal re-inforcing plate disposed over said fibre filler member and extended longitudinally along the major portion of said base-member and having a forward lateral extension disposed over the lateral extension of said fibre filler member, and means attaching said metal re-inforcing plate to said base-member.

In testimony whereof, I have signed my name to this specification.

GEORGE A. HURLEY.
